JOSEPH C. THEBERATH, OF LAKEWOOD, OHIO, ASSIGNOR OF ONE-THIRD TO WILLIAM D. GRAFF, OF LAKEWOOD, OHIO.

SIGNATURE-COLLECTING MECHANISM.

1,393,924.

Specification of Letters Patent. Patented Oct. 18, 1921.

Application filed November 9, 1918. Serial No. 261,865.

To all whom it may concern:

Be it known that I, JOSEPH C. THEBERATH, a citizen of the United States, residing at Lakewood, in the county of Cuyahoga and State of Ohio, have invented a certain new and useful Improvement in Signature-Collecting Mechanism, of which the following is a full, clear, and exact description, reference being had to the accompanying drawings.

The general aim of my present invention is to improve and in some respects to simplify the construction and operation, and to increase the capacity, of the signature collecting and stuffing mechanism disclosed in my former Letters Patent No. 1,149,546, issued August 10, 1915.

Like my former machine, the present one is designed with particular reference to the collecting and stuffing of the sections of large newspapers, such as Sunday editions. In the production of newspapers comprising more than one signature or section, the individual sections are folded as they are discharged from the printing press and afterward nested together or inserted one within another. It is the function of my machine to accomplish this latter step, and, to the attainment of this result in the most complete manner, my present invention comprehends, in its more elaborate form, the idea of including a plurality of receiving stations so that the signatures or sections may be picked up progressively and inserted successively, eliminating considerable handling of the papers and rendering the compiling of a completed edition very simple and practically automatic.

From this reference to newspaper work it must not be supposed that my invention is limited to that field alone, for it will be understood that the same is equally as well adapted to the gathering and stuffing of folded leaves or signatures constituting pamphlets, books or the like.

In carrying out my present invention I follow the general arrangement of parts and mode of operation of my former machine, but materially alter some of the vital elements, and add others, to the end that the machine works with greater precision and is capable of operating at a higher speed and with less attention than its predecessor.

Specific objects sought to be attained are the provision of means for insuring the proper entrance of the conveying blade into

the fold of the signature or section; the provision of supporting means for the receiving signatures having an intermittent accumulative upward movement so that, as the signatures are removed from the stack, the topmost signature will be maintained at a proper elevation to receive an entering signature; the association therewith of a stop for restraining the topmost signature against undue elevation; and the inclusion, with means for opening the receiving signature, of mechanism for practically simultaneously retracting the aforesaid stop and slightly lowering the supporting means thereby to relax the receiving signature to facilitate the insertion of the entering signature; and the provision of ejecting mechanism actively engaging opposite sides of a completed article or paper thereby to positively remove it from the machine and prevent displacement of its component parts or disturbing its compact condition.

A further object is the provision of a unique clutch arrangement, capable of a very fine adjustment and which is positive of action, for accomplishing with a high degree of accuracy the intermittent accumulative upward movement of the support or table for the receiving signatures.

Other objects will become apparent as I proceed to describe the invention in detail, reference being had to the accompanying drawings wherein Figure 1 is a plan view of the machine; Fig. 2 is a sectional side elevation, the plane of section being indicated by the line 2—2 of Fig. 1; Fig. 3 is a vertical section taken substantially on the line 3—3 of Fig. 2; Fig. 4 is a horizontal section on the line 4—4 of Fig. 3; Fig. 5 is a section substantially on the line 5—5 of Fig. 1; Fig. 6 is an enlarged fragmentary sectional side elevation in the vicinity of the receiving end of the ejection mechanism; Fig. 7 is a detail in perspective of the cam for retracting the stop or weight and performing other acts pertaining to the relaxing and opening of the receiving signature; Fig. 8 is a horizontal section on the line 8—8 of Fig. 3; Fig. 9 a section on the correspondingly numbered line of Fig. 8; Fig. 10 shows in perspective and in separated condition certain elements of the mechanism for opening the receiving signatures; Fig. 11 is a perspective view of the clutch mechanism through which the supporting means for the receiving signatures is elevated; and

Fig. 12 is a diagrammatic representation of a modification of the invention incorporating a plurality of receiving tables or stations.

The form of the machine illustrated in Figs. 1 to 11 incorporates generally the following elements: A supply station A, a receiving station B, mechanism designated C for opening a receiving signature at station B and conveying another signature from station A and inserting it into the receiving signature, thereafter carrying both into the ejecting mechanism D; these several elements being supported in proper relation to each other by and within a frame 1.

15 Situated at the supply station A is an adjustable table 2 (Fig. 5) having a sub-structure 3 guided vertically within uprights of the frame 1 and adapted to be held at a properly adjusting elevation by means of a screw 4 that is shown as threaded through an element 5 of the sub-frame and bearing at its lower end upon a thrust plate 6, carried by cross members of the frame 1. Supported in proper relation to table 2, by 20 a superimposed frame 1^a, are the end plates 8 and 9 and a rear plate 10, while a front plate 11 is adjustably connected to a cross member of the superimposed frame, as by means of bolts 12 having thumb nuts 13 and 25 passing through slots in rails 14 (Fig. 2), that are attached to the front plate.

An elevator table occupies receiving station B (Fig. 2) and the top 16 thereof is composed of two sections hingedly connected on a transverse axis, as indicated at 17, so that both sections may be inclined downwardly from the hinge, the rear section at a lesser angle from the horizontal than the front. The rear section is shown as hingedly 30 connected at 18, to a sub-frame 20 to permit of this adjustment. The sub-frame 20 is guided vertically within uprights of the frame 1, and pivoted at 22 to cross members thereof are opposed L-shaped levers 21, 35 the levers having connection through links 23, with the hinge 17 of the table top 16. The lower ends of the L-shaped levers have pins 24 that bear upon the front edges of rails 25, said rails being adjustably connected at their upper ends at 26 to members of the sub-frame, and similarly connected at their lower ends, through links 27, with slotted members 28 of the sub-frame. By varying the inclination of the 40 rails 25, the lower ends of the L-shaped levers are swung in a forward or rearward direction on their pivots 22 to elevate or lower through links 23, the hinge point of the sections of the table top 16, for a purpose which will be explained later.

The table top 16 and its entire sub-structures are designed to be reciprocated at each cycle of the machine, and, at the same time, to be gradually fed upward—as previously 45 expressed—with an accumulative movement.

The reason for the reciprocatory movement is to relieve the top signature on table 16 of pressure and allow it to open or separate more readily as the entering signature is inserted; and the accumulative movement is 70 obviously for the purpose of advancing the table to maintain the top of the stack of receiving signatures at the proper elevation. The mechanism whereby this is accomplished will now be described.

75 A shaft 30 is supported transversely of the machine below sub-frame 20 and in fixed relation to the main frame 1, the same being shown as carried within brackets 31, rising from a plate 32, that is supported within the main frame. A yoke or frame 33 is journaled upon shaft 30 and carries at its forward end a shaft 35, the same being in the form of a disk having a peripheral flange 37. Journaled upon the clutch 80 element is a cylindrical member 38 having a radially disposed boss 39 to which is attached a rod 40. The lateral notches of a pair of grippers 41 and 42 embrace the flange 37 of the clutch element, and springs 85 43 tend to elevate their bifurcated ends, the spring of the gripper 41 being anchored to the member 38, while that of the gripper 42 is anchored to a collar 44 on shaft 30. The opposite ends of the respective grippers 90 engage a pin 45 which extends laterally from the boss of member 38, and a pin 46 which projects downwardly and forwardly from collar 44. This disposition of the grippers 95 causes them to resist movement relative to 100 the clutch element in a clock-wise direction, as the parts are viewed in Figs. 2 and 11, wherefore it will be seen that a depression of rod 40 will cause it to transmit, through the intervention of the pin 45 and gripper 105 41, a slight rotary motion to the clutch element, while the other gripper will yield to such a movement. Now, upon the elevation of rod 40, the gripper 41 will be carried with it upwardly about the flange 110 of the clutch element, while gripper 42, in the meantime, holds the clutch element against return movement. Thus it will be seen that this organism, constituting a unique clutch arrangement, acts similarly to 115 a pawl-and-ratchet contrivance, the gripper 41 answering as the pawl to advance the clutch element which is the equivalent of the ratchet, while the gripper 42 serves as a detent to prevent the return movement 120 thereof.

125 A shaft 50 is suitably supported transversely of the main frame and extends across the rear end of yoke 30 and carries cams 51 for coöperation with the sides of the yoke. Consequently, upon each rotation of the shaft, the yoke will be rocked to raise and lower shaft 35 that is carried by its forward end. The shaft 50 is also equipped with an eccentric 52, encircled by 130

a strap 53 that has adjustable connection, through the link 54, with rod 40. Therefore, as shaft 50 rotates it will vibrate arm 40 and, through the clutch arrangement 5 above described, will transmit an intermittent rotary motion to shaft 35. The extent to which rod 40 is vibrated and likewise the angular movement of shaft 35, may be altered by the adjustment of link 54 along 10 the rod. Shaft 35 has fixed to it a pinion 56 that is in constant mesh with a rack 57, carried by the sub-frame 20 of table 16. It follows, therefore, that as the shaft 50 is driven, it will not only cause a vertical 15 reciprocation of the table 16 by reason of the oscillation of yoke 35, but it will effect a gradual elevation thereof because of the vibration of rod 40, and the consequential intermittent rotation of shaft 35 and pinion 20 56. The table may be abruptly lowered by pressing downward simultaneously on the forward ends of the two grippers 41 and 42 causing them to release their bite upon the flange of the clutch element, thereby permitting 25 it and the shaft 35, with pinion 56, to rotate freely.

Mechanism C involves a shaft 60 that is supported vertically within the main frame 1; and slightly below the plane of table 2 30 the shaft has secured to it a disk 61. This disk carries a stub shaft 62 on the lower end of which is mounted an arm 63 having, at its free end, a roller 64 that is guided within a cam groove 65 of a plate 66 (Figs. 35 8 and 9) secured to cross members 67 of the main frame. Mounted upon the stub shaft 62, to oscillate in unison with the arm 63, is a gear 68 which meshes with a pinion 69 on a second stub-shaft 70, having 40 a head 71 above the disk and to which is secured a conveyer blade 73. As the shaft 60 is rotated and the roller 64 of the arm 63 traverses groove 65, the blade, while traveling through its orbit about the shaft 45 will be rocked in such manner, by reason of the shape of groove 65, as to transmit, through gear 68 and pinion 69, a movement to the blade resulting in its being projected into the fold of the lowermost signature 50 at the receiving station A and assuming therein a position substantially parallel to the folded edge of the signature and thereafter moving, while substantially radial with respect to the shaft, through substantially 55 90 degrees until it deposits the signature within the topmost signature at the receiving station B, the blade subsequently swinging farther to carry the two signatures into the ejector mechanism D, and finally 60 being withdrawn from the signatures to swing with an accelerating speed upon its pivot until its forward end is again in a position to enter the next signature at the supply station. This movement of the blade 65 takes place during a rotation of the disk 61,

or what may be regarded as a complete cycle of operation of the machine.

It may be explained at this time that the signatures or newspaper sections are deposited upon table 2 within the confines of 70 the end walls 8 and 9 and rear wall 10, with their folded edges adjacent or bearing against plate 11. The plate 11 is adjusted so as to permit the passage of only one signature beneath it, while the table is set at 75 a proper elevation to locate the space always occurring within the folded edge of a folded sheet or signature at the precise elevation of the blade 73. As the blade withdraws a signature from the supply station 80 it conveys it across a shelf 75 to the receiving station B.

To prevent slight vertical displacement of the free end of the blade as it enters the fold of the signature, I provide a guide 85 therefor comprising a roller 76 that is supported by a bracket 77 from the frame adjacent and below the lower edge of the end wall 9. Above roller 76 is movably sustained a roller 78 by an arm 80 that is pivoted at 81 to a remote portion of frame 1^a. The shaft 60 carries, at its upper end, a cam element 84 having a cam portion 85 adapted to engage a roller 86 of arm 80 and elevate the same and consequently the roller 78 after 95 the roller has performed its function of properly guiding the end of the blade into the fold of the signature, thereby to relieve the blade of all unnecessary friction.

Preparatory to inserting a signature with- 100 in the topmost signature at the receiving station, it is necessary to open the latter signature. In the present machine this is accomplished by mechanism which I will now describe.

Mounted for oscillation and slight vertical movement within a hollow boss 88, rising from an angle plate 89 of the superimposed frame 1^a, is a shaft 90 having a finger 91 at its lower end that repose normally 105 in the plane of the top signature of the receiving station. A series of pins 92 radiate from a member 93 that is fixed to the lower end of shaft 90 for coöperation with a segmental flange 94 of the former cam element 84. This segmental flange is interrupted by notches 95, as clearly shown in Fig. 7, and as the cam rotates these notches cooperate with the previously mentioned pins 93, on the principle of crown and pin gears, and cause an oscillation of shaft 90 through substantially a quarter of a circle and sufficiently to insert the finger 91 well into the signature. By referring particularly to Figs. 2 and 10, it will be seen that 110 the shaft 90 is equipped with a head 96 which occupies the interior of the boss 88, and that pins 97 extend laterally from the head into notches 98 of the boss. The bottom walls of these notches constitute the 115 120 125 130

cams which the pins 97 ascend as the shaft 98 is rotated, thereby to cause an elevation of the shaft. The rise of the shaft lifts finger 91 and opens the signature, this condition prevailing while the extended portion of the flange 94 coöperates with the last pin 93 of the series. A spring 100 surrounds the boss 88 and has one of its ends anchored to a pin 101 that projects from the side of the boss, and its opposite end attached to one of the pins 97. This spring tends to maintain the shaft and consequently the finger 91 in normal position.

The finger 91 is accurately guided into the fold of a signature by a pair of guide rollers 102 and 103, the former being stationary and the latter carried by an arm 104 that is pivoted at 105 to the frame 1^a and has a roller 106 which is adapted to be engaged by the former cam portion 85 of cam element 84, substantially identical with the corresponding elements associated with blade 73.

For maintaining the topmost signature at the receiving station against undue elevation, I provide a stop 110, in the present instance in the form of a weight, that is carried by arms 111 which have eccentric straps 112 at their upper ends encircling eccentrics 113 on a shaft 114. This shaft is journaled in brackets 115 on the superimposed frame 1^a, and beyond the inner bracket, the shaft has fixed to it an arm 116 carrying at its free end a roller 117 that engages the top of cam element 84. The element has a cam portion 118 adapted to engage the roller and swing the arm upward to oscillate the shaft 114 sufficiently to slightly retract the stop or weight 110 through the action of eccentrics 113. This is timed to occur at the moment the table 16 is depressed through mechanism already described, thus to relax the signatures and facilitate the entrance of blade 91 into the fold of the topmost signature, as well as to effect a free opening of the signature to receive the one conveyed thereto by blade 73. It may be pointed out at this time that the slight downward inclination given the rear section of table 16 causes the space within the fold of the topmost signature to occupy a substantially horizontal position in alignment with finger 91; and it is obvious that the downward inclination of the front section contributes to an effectual separation of the free edges of the signature.

Just to the rear of the receiving station are supported, within the main frame, parallel shafts 120 and 121, the latter having its ends guided within slots 122 so as to be capable of a movement toward and from shaft 120. These shafts carry rollers 123 over which conveyer belts 124 are engaged, the belts also extending over pulleys 125 65 that are pivoted within brackets 126 se-

cured to rods 127 which are supported in the outer end of an extension 1^b of the frame. Knurled portions 128 of rollers 123 insure effective gripping of the signatures as they are projected between the rollers of the respective shafts 120 and 121 by the blade 73. While the upper roller is permitted to rise and fall according to the thickness of the articles fed between the rollers and belts, its weight causes it to bear down upon the articles with sufficient pressure to positively feed them. The shafts 120 and 121 are geared together by the arrangement of gears shown in Fig. 6. The lower shaft is equipped with a gear 130, while the upper shaft has secured to it gear 131; and the latter is positively driven from the former through intermediate pinions 132 carried upon shafts 133. These shafts 133 are maintained a fixed distance apart and from shafts 120 and 121 by a series of links 134.

The lower shaft 120 carries, at its outer end, a pulley 136 that may be driven through a belt 137 from any suitable source of power, as motor 138. The inner end of the same shaft 120 is equipped with a bevel pinion 140 that meshes with a similar pinion 141 on the upper end of a shaft 142, journaled at its upper end within the frame and at its lower end within a portion of a gear casing 143, the shaft having a worm 144 within the casing that meshes with a worm wheel 145 that is fastened to the previously mentioned shaft 50. Shaft 50 extends from the gear casing toward and within a short distance of vertical shaft 60 and is geared thereto through miter gears 148. By this arrangement of gearing the rollers and belts of the ejector mechanism D may be operated at a comparatively high rate of speed, while mechanism C is driven with greater power and at a desirably lower speed.

In Fig. 12 I have illustrated diagrammatically a modification of the invention incorporating a supply station A and several receiving stations B, ejector D, and common operating mechanism C. In an embodiment of this character it is clear that no essential change is necessary in the mechanism hereinbefore described, but only that the elements associated with each of the receiving stations be multiplied according to the number of receiving stations.

In the operation of this form of the invention, a signature is picked up at the supply station and conveyed to the first receiving station and inserted in the topmost signature thereof, after which the two signatures are carried on to the next receiving station and inserted within the topmost signature thereof and so on until the compiled edition is deposited in the ejector D.

Having thus described my invention, what I claim is:—

1. In a machine of the character set forth,

the combination of a support for signatures or the like, means for inserting signatures successively within those on the support and removing the entering and receiving signatures from the support, a rotary element having operative connection with the support so that upon rotation thereof in one direction said support will be advanced, an oscillatory member within which the rotary member is sustained, and mechanism for oscillating the sustaining member and imparting intermittent rotation to the rotary element.

2. In a machine of the character set forth, the combination of a support for signatures or the like, means for inserting signatures successively into those on the support and for removing the inserted and receiving signatures from the support, a rack connected with said support, a pinion coöperating with the rack, an oscillatory member within which the pinion is supported for rotation, and mechanism for oscillating the member and imparting intermittent rotation to the pinion.

3. In a machine of the character set forth, the combination of a support for a stack of signatures or the like, means for inserting signatures successively into those of the stack and for removing the inserted and receiving signatures from the support, of mechanism for imparting an intermittent reciprocatory and accumulative advance movement to the support, said means being adjustable as to the extent of the accumulative movement at each reciprocation.

4. In a machine of the character set forth, the combination of a support for signatures or the like, means for inserting signatures successively into those on the support and for removing the inserted and receiving signatures from the support, a rack connected with the support, a pinion coöperating with the rack, a clutch element rotatable with the pinion, a member adapted to oscillate on the axis of said element, grippers carried by the member for coöperation with the clutch and acting when moved in one direction to impart rotation to the element while serving to retain the element against rotation in the opposite direction, an oscillatory frame supporting the pinion clutch element and member, a shaft, a cam on the shaft for coöperation with the frame thereby to oscillate the frame as the shaft is rotated, an eccentric upon the shaft, and operative connections between the eccentric and the aforesaid member, said connections being adjustable thereby to impart variable intermittent movement to said member.

5. In a machine of the character set forth, the combination of a support for signatures or the like, means for inserting signatures successively into those on the support and for removing the inserted and receiving

signatures from the support, a rack connected with the support, a pinion coöperating with the rack, a clutch element rotatable with the pinion, a member adapted to oscillate on the axis of said element, grippers carried by the member for coöperation with the clutch element and acting when moved in one direction to impart rotation to the element while serving to retain the element against rotation in the opposite direction, an oscillatory frame supporting the pinion clutch element and member, a shaft, a cam on the shaft for coöperation with the frame thereby to oscillate the frame as the shaft is rotated, an eccentric upon the shaft, and operative connections between the eccentric and the aforesaid member thereby to impart intermittent movement to said member.

6. In a machine of the character set forth, the combination of a support for a stack of signatures or the like, means for inserting signatures successively into those of the stack and for removing the inserted and receiving signatures from the stack, a stop for restraining the signatures against undue advance movement, and mechanism for imparting advance movement to the support and for retracting the same and the aforesaid stop substantially simultaneously with the insertion of a signature.

7. In a machine of the character set forth, the combination of a support for a stack of signatures or the like, means for inserting signatures successively into those of the stack and removing the inserted and receiving signatures from the stack, means for advancing the support to compensate for the removal of the signatures, and means for retracting the support thereby to relax the signature during the inserting operation.

8. In a machine of the character set forth, the combination of a support for signatures or the like, a member insertible within the fold of a signature on the support, a guide for said member, and means for releasing the guide from the member after the same has been inserted within the signature.

9. In a machine of the character set forth, the combination of a support for signatures or the like, a member insertible within the fold of a signature on the support, guides engaging opposed sides of the member, and means for separating the guides after said member has been inserted.

10. In a machine of the character set forth, the combination of a support for signatures or the like, a member insertible into the fold of a signature on the support, a guide element supported at a fixed plane for determining the elevation of the member, a second guide element for engaging the member and holding it in contact with the first, and means for retracting the second guide element after the member has been inserted.

11. In a machine of the character set forth,

the combination of an element operating in a given plane and insertible into the fold of a signature, and a signature support consisting of two members adapted to be disposed slightly angularly with respect to each other so as to maintain the space within the fold of a signature sustained by the support in a substantially horizontal position.

12. In a machine of the character set forth, 10 the combination of an element operating in a given plane and insertible into the fold of a signature, a support for the signature consisting of members slightly inclined with respect to each other so as to support a 15 signature with the space within its fold substantially horizontal, and means for varying the angular relation between said members.

13. In a machine of the character set forth, the combination of an element operating in a given plane and insertible into the fold of a signature, a support for signatures comprising a sub-structure, a pair of hinged plates whereon the signatures are adapted to be supported, one of said plates being pivotally connected to the sub-structure, and 20 means carried by the sub-structure for adjusting vertically the hinge connection between the plates so that signatures of various thickness may be supported thereon with the space within their folds substantially horizontal. 25

In testimony whereof, I hereunto affix my signature.

JOSEPH C. THEBERATH.
